CLAIM

The ornamental design for a water misting fan, as shown and described.

DESCRIPTION

FIG. 1 is a first perspective view of the water misting fan showing our new design;

FIG. 2 is a second perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines immediately adjacent the shaded areas represent the bounds of the claimed design while all other broken lines are directed to unclaimed portions of the water misting fan; the broken lines form no part of the claimed design.

1 Claim, 5 Drawing Sheets(56)
